UNITED STATES PATENT OFFICE.

EDWIN R. STUCKY, OF LOUISVILLE, KENTUCKY, ASSIGNOR TO AUTOSALES GUM & CHOCOLATE COMPANY, OF NEW YORK, N. Y., A CORPORATION OF NEW YORK.

DESIGN FOR A GLASS DISPLAY-JAR.

45,898.

Specification for Design.

Patented June 2, 1914.

Application filed March 27, 1914. Serial No. 827,759. Term of patent 14 years.

To all whom it may concern:

Be it known that I, EDWIN R. STUCKY, a citizen of the United States, residing at Louisville, Kentucky, have invented a new, original, and ornamental Design for Glass Display-Jars, of which the following is a specification, reference being had to the accompanying drawing, forming a part thereof.

is a plan view of a glass display jar illustrating my new design.

I claim:

The ornamental design for a glass display jar as shown.

EDWIN R. STUCKY.
